(57) **CLAIM**

I claim the ornamental design for a hammerhead, as shown herein.

DESCRIPTION

FIG. 1 is a perspective view of the hammerhead;
FIG. 2 is another perspective view of the hammerhead
looking from a different perspective than FIG. 1;
FIG. 3 is a back elevation view of the hammerhead;
FIG. 4 is a front elevation view of the hammerhead;
FIG. 5 is a right side elevation view of the hammerhead;
FIG. 6 is a left side elevation view of the hammerhead;
FIG. 7 is a top elevation view of the hammerhead; and,
FIG. 8 is a bottom elevation view of the hammerhead.
